US0D1016098S

(12) **United States Design Patent** (10) **Patent No.:** **US D1,016,098 S**
(45) **Date of Patent:** **** Feb. 27, 2024**

(54) **MODULAR IMPELLER**

(71) Applicant: **Life Technologies Corporation**,
Carlsbad, CA (US)

(72) Inventors: **Nephi D. Jones**, Newton, UT (US);
Jason D. Brown, Logan, UT (US)

(73) Assignee: **LIFE TECHNOLOGIES
CORPORATION**, Carlsbad, CA (US)

(**) Term: **15 Years**

(21) Appl. No.: **29/773,911**

(22) Filed: **Mar. 12, 2021**

Related U.S. Application Data

(63) Continuation of application No. 17/165,564, filed on
Feb. 2, 2021.

(57) **CLAIM**

The ornamental design for a modular impeller, as shown and
described.

DESCRIPTION

FIG. 1 is a top perspective view of a modular impeller
showing our new design;

FIG. 2 is a bottom perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and,

FIG. 8 is a bottom plan view thereof.
